4 Claims. (Cl. 19—123)

This invention relates to the combing of textile fibres. In the processing of wool fibres, after the fibres have been passed through the backwash and gilling stages or other stages of preliminary preparation, they are passed through a comb to further align the fibres and to separate the long fibres from the short fibres and also to remove vegetable matter from the fibres. The sliver which emerges from the comb is referred to as "top" sliver and the short fibres, vegetable matter, neps etc. left behind is referred to as "noil." Combs most commonly used in textile mills using the "Bradford" system are of the type known as the "Noble" comb. These comprise broadly a large circle of upstanding pins and two smaller circles of pins located within the large circle and diametrically opposite one another. The large circle is rotatably mounted and carries around its periphery a number of balls of sliver mounted on rollers and having their free ends embedded in the pins of the large circle. The small circles are also rotatable and travel at their points of common tangency with the large circle with a peripheral velocity equal to that of the large circle. Sliver is fed from the balls by the action of feed knives which unwind the balls by a given amount while the end of the sliver to be combed is held by the pins. After this occurs the sliver is lifted from the pins of the large circle onto a feed plate where it straightens out or is "set-over." At the stage where the rotating outer circle reaches its point of common tangency with one of the inner circles the free end or fringe of the sliver drops back onto the pins of the outer and inner circles and is forced into them by means of a dabbing brush. As the outer circle continues to rotate the pins of the two circles separate and the fibres are combed through the pins leaving now two fringes one on the small circle and one on the large circle. The long fibres of these fringes are then drawn off the pins by each set of drawing off rollers and fed to a common point to form an output sliver. Since there are two small circles and two fringes are formed at each small circle the output sliver is composed of fibres coming from four separate points. The noil left on the pins of the small circle is subsequently removed by noil knives.

The rate of feeding input sliver to the comb is determined by the amount of set-over resulting from the feeding of the sliver from the balls by the action of the feed knife. The amount of wool set-over, however, is not dependent only on the position of the feed knife but is also affected by changes in the tension in the ball of input sliver and variations in the weight of the sliver per unit length.

It has long been thought that the quality of the output sliver is best controlled by controlling the set-over during the combing operation. The commonly accepted criterion for good combing is a constant set-over since it has been thought that if the set-over is kept constant then the tear ratio (i.e. the ratio of top to noil) will be kept constant. Investigations have, however, shown that the maintenance of a constant set-over would not always produce the desired constant tear ratio.

The feed rate during combing is at present controlled by an operator who observes the set-over at regular intervals of say 20 minutes and endeavours to maintain a constant set-over by varying the setting of the feed knives where necessary, or by an automatic feed knife control

2

which varies the position of the knife at each revolution of the comb to compensate for changes in ball tension.

When corrections are made manually, the constancy of the set-over depends on the subjective assessment of the over-looker and the frequency with which he attends the comb. Automatic systems, which still depend on the over-looker for the initial setting, make a small correction to the feed knives every revolution of the large circle. The magnitude of this correction presupposes that the input weight is accurately known, that the drag from the creels remains constant, that the tension varies at a known rate and that the tension changes are the same between sets of balls. Variations produced by the punch box, varying moisture content and standing time make these conditions rarely satisfied. In addition neither form of correction makes any attempt to maintain a constant set-over when rapid tension variations are experienced during the run in and run out periods of the comb load. Furthermore, neither method of correction is, in fact, sufficiently accurate successfully to maintain constant set-over even during normal running combing operation in which the set-over was inspected and, if necessary, corrected every 5 minutes in order to keep it constant, the average output weight was found to vary from 116 to 136 drams per minute or by plus or minus 8% on a range mean of 126 drams per minute. In the same tests the tear ratio was found to vary between 6.6 and 8.4, a variation of plus or minus 12% on a range mean of 7.5. Thus, in a test which was apparently closely controlled, considerable variations both in output weight and tear ratio occurred. It is thought that the reason for these variations, which are short term with respect to the time taken to comb a load, is the non-homogeneity of the input sliver. For instance, if a thicker than normal sliver is fed into the comb and the set-over is maintained constant then the output rate will be higher. Furthermore, if a sliver is too thick then it will become difficult to draw the fibres through the comb and fibre breakage will occur during the combing operation. This will result in the production of a greater quantity of noil and a corresponding decrease in the tear ratio.

In the light of the above investigations it is now proposed according to this invention to control the input to the comb so as to give a substantially constant production rate i.e. to give an output sliver having a substantially constant number of fibres in cross-section. In accordance with the present invention, variations in the average number of fibres in the cross-section of the output sliver are corrected by sensing the thickness of the sliver and if necessary, in response to those measurements, correcting the rate at which input sliver is fed to the comb in order to correct for variations from a predetermined standard in the thickness of the output sliver.

More particularly, the invention provides apparatus for maintaining the thickness of output sliver from a "Noble" comb substantially constant, which apparatus comprises means for detecting variations in the thickness of the output sliver, means operated by the detecting means to generate electrical signals in response to the detection of variations from a predetermined standard thickness by more than a predetermined amount, means to average the signals over a finite period and means actuated by the average of the signals to correct the input of textile material to the comb when the average thickness of the output sliver over the finite period varies from the predetermined standard by more than the predetermined amount. Normally the apparatus will also include means operable, after each correction is made, to delay any further correction until such time as the previously corrected sliver reaches the detecting means. Preferably the means to correct the input of textile material to the comb

comprises an electric motor adapted to vary the position of the feed knives of the comb.

One form of apparatus for carrying the invention into effect comprises a pair of spring-loaded conventional tongued and grooved detecting rollers which are substituted for the calendar rollers of the can coiler-head which receives the output sliver from the comb. Movement of the rollers in response to variations in thickness of the output sliver is caused to operate a micro-switch which controls the supply of power to the coil of a relay which in turn is adapted to operate switches controlling the supply of power to a reversible correcting motor adapted to vary the position of the feed knives of the comb. The apparatus also incorporates a timing mechanism for delaying the operation of the correcting motor.

This apparatus will now be more fully described with reference to the accompanying drawings in which:

FIGURE 1 is a schematic cross-sectional view of part of a combing machine showing the arrangement of the drive from the correcting motor to the feed knives,

FIGURE 2 is a circuit diagram of the means to supply power to the coil of the contacting meter,

FIGURE 3 is a circuit diagram showing the operation of the contacting meter and the correcting motor control switches,

FIGURE 4 is a diagram of the time delay circuit, and

FIGURE 5 is a schematic end elevation of the control cam on the timing motor.

Referring now to FIGURE 1, the numeral 1 represents the large circle of a Noble comb and 2 represents a conventional feed knife, one end of which is pivoted and the other end of which is forced downward against the pressure of a spring 3 by pivoted lever 4 which presses on the top of the push-rod 5 and is adapted to be moved up or down by the collar 6 on a column screw 7. The column screw 7 is driven through a gear box 8 by means of the reversible correcting motor 9 and a further shaft 10 leads from the gear box to another similar knife control unit on the opposite side of the comb.

In FIGURE 2, the switches 11 and 12 represent two contact positions of a micro-switch actuated by movement of the detecting rollers 22 in response to variations in thickness of the output sliver, contact 11 being made when the sliver is too thick and contact 12 being made when the sliver is too thin. Over a period of time the thickness of the sliver will normally vary above and below the desired value causing the contacts 11 and 12 to be made or broken. The making of the contact 11 will cause the condenser 13 to be charged and the making of the contact 12 will cause the condenser 14 to be charged. The circuit components associated with these condensers are so chosen that the time constant is about 20 seconds. Thus at any instant the potential across the terminals of the meter coil 15 will be a function of the average charge on the two condensers over the preceding 20 seconds. When this average charge is such as to indicate a departure from a predetermined value of the thickness of the output sliver by more than 1%, one or other of the contacts 16, 17 on the contacting meter shown in FIGURE 3 will be made.

Provided that the switches on the timing circuit (to be more fully explained hereinafter) are in the correct position and provided the comb is operating, closing of the contact 16 will cause the relay 18 to be energised and this will cause the switch 19 to close. Closing of the switch 19 will energise the relay 20 and this will cause the switch 21 to close to supply power to the correcting motor 29 and cause it to operate in the direction for raising the position of the feed knife 2. Similarly, closing of the meter on the contact 17 will cause the relay 23 to be energised and this will close the switch 24 thus energising the relay 25 and closing the switches 26 to cause the motor 9 to rotate in the opposite direction for lowering the feed knife.

As previously pointed out, after a correction has been

made, it is necessary for a further correction to be delayed until the effect of the first correction is detected by the detecting rollers. This is done by the timing circuit and the timing cam illustrated in FIGURES 4 and 5. The timing cam 27 is driven by a suitable electric motor 28 and is provided on its periphery with a recess 29 and on its face with an abutment 30. When the timing motor operates the timing cam revolves in the anti-clockwise direction at a speed of one revolution in 22 seconds and when this occurs the switch 31 will close whilst its trigger is opposite the recess 29, in this case for about 2 seconds, and the switch 32 will close when its trigger moves off the abutment 30.

The operation of the apparatus is as follows:

With the comb running, output sliver will pass through the detecting rollers and will normally fluctuate above and below a predetermined thickness causing the micro-switch associated with the rollers to close on one or other of the positions indicated as contacts 11, 12 in FIGURE 2 thus charging the condensers 13, 14 and when the average departure of the sliver from the predetermined thickness over a 20 second period exceeds 1% one or other of the contacts 16, 17 on the contacting meter will be made, depending on whether the average variation is above or below the predetermined thickness. If, say, the sliver is too thick, the contact 16 will be made thus closing the switch 21 as previously explained and also starting the timing motor 28. This will cause the cam 27 to rotate causing the switch 31 to close thus supplying power to the correcting motor 9 and causing the feed knife to be raised. The correcting motor will continue to operate until the recess 29 on the timing cam passes the trigger of the switch 31 (in this case, after about 2 seconds) when this switch will again open and the power to the motor 9 will be cut off. Rotation of the cam 27 will, however, have allowed the switch 32 to close so that even if the contact 16 opens the timing motor will continue to run until a full revolution is completed when the switch 32 will be opened by the abutment 30. It, at the completion of the cycle, neither of switches 16, 17 are closed the timing motor will stop with the cam in the position shown in FIGURE 5 until such time as the closing of one of those switches initiates another cycle. If, on the other hand, one of the switches 16, 17 is closed at the end of the cycle, then of course the cam 27 will continue to rotate and a further correction will be made.

When the comb is stopped, it is desirable simultaneously to stop the action of the correcting motor and to place the timing cam in such a position that a correcting cycle will not be commenced immediately the comb is restarted. This is done by means of a micro-switch 33 in the circuit of the contacting meter and a change-over switch 34 in the timing motor circuit, both of which are actuated by the comb starter switch, and by a micro-switch 35 in the timing motor circuit actuated by the abutment 30 on the timing cam. When the comb stops, the micro-switch 33 is opened thus preventing the relays 18 and 23 from being energized and preventing the motor 9 from operating. The change-over switch 34 moves to position B and the timing cam continues to rotate until the abutment 30 triggers the micro-switch 35 causing it to open and stop the motor with the cam in such a position that the recess 29 is just on the anti-clockwise side of the trigger of the micro-switch 31. Thus when the comb is re-started it must run for at least about 20 seconds before a correction is made.

In an alternative arrangement, the contacting meter may be replaced by a pair of rectifiers adapted to pass current in opposite directions to the relays 18, 23 according to the magnitude and direction of the potential difference between the condensers 13, 14.

The above apparatus and method of controlling the combing action substantially reduces long term variations in the weight of output sliver and produces a relatively constant tear ratio. The detecting device used is one which

measures, in effect, the number of fibers in the cross-section of the sliver, since by suitable choice of spring pressure it can be made relatively independent of moisture regain so that in the ideal condition there is obtained an output sliver which is of substantially constant thickness along its length and between comb loads. Furthermore, due to the fact that the length of wool set over into the pins is varied in accordance with variations in the thickness of the input sliver the occurrence of an abnormally thick sliver does not give rise to greatly increased fibre breakage. The tear ratio is thus kept relatively constant as is illustrated by tests which were conducted with the process controlled and corrected in accordance with the present invention. In tests similar to those previously quoted, with the comb controlled, the variation in output weight was reduced to between 120 and 125 drams per minute or plus or minus 2% on a range mean of 122.5 drams per minute and the variation in tear ratio was reduced to between 7.3 and 8.1 or plus or minus 5.2% on a range mean ratio of 7.7.

Thus it will be seen that, contrary to the present practice, it is not always desirable to maintain a constant set-over but rather should the set-over be varied if necessary to give a constant production rate. If this is done then the output sliver will be more uniform, the fibre breakage in the comb will be reduced and the tear ratio will be more constant.

I claim:

1. Apparatus for controlling the combing of textile fibres in a combing machine of the type known as a "Noble" comb, comprising means for detecting variations from a predetermined standard thickness of the output sliver from the comb, means operated by said detecting means to generate electrical signals corresponding to the detected variations in thickness of the output sliver, means averaging the generated signals over a finite period, and means actuated by the average of said signals to vary the input of textile fibres to the comb when the average of the

signals corresponds to an average thickness of the output sliver over said finite period varying significantly from said predetermined standard thickness.

- 5 2. Apparatus as in claim 1, wherein said combing machine has movable feed knives regulating the input of textile fibres to the comb, and wherein said means for varying the input of textile fibres to the comb includes a reversible motor adapted to vary the position of said feed knives of the comb.
- 10 3. Apparatus as in claim 1, further comprising means operable, following a variation in the rate of input of textile fibres to the comb, to delay any further variation in the rate of input until such time as the effected variation exerts an influence on the thickness of the output sliver influencing said detecting means.
- 15 4. Apparatus as in claim 1, wherein said combing machine has movable feed knives regulating the input of textile fibres to the comb, and wherein said means for varying the input of textile fibres to the comb includes a reversible motor adapted to vary the position of the feed knives of the comb, and further comprising means operable, following a variation in the position of the feed knives, to delay any further variation in the position of the feed knives until such time as the effected variation exerts an influence on the thickness of the output sliver influencing said detecting means.
